UNITED STATES PATENT OFFICE.

EDDIE O. SIMPSON, OF TARRANT, ALABAMA, ASSIGNOR OF ONE-HALF TO FELIX I. TARRANT, OF BIRMINGHAM, ALABAMA.

INTERLOCKING STOVEPIPE BLANK.

Application filed January 28, 1927. Serial No. 164,168.

This invention has general reference to sheet-metal piping such as is commonly used for stove pipe, and relates more particularly to improved means for securing together the 5 lateral edges of an initially flat blank of sheet metal when it is subsequently bent to the form in which it is intended to be used as a section or length of such piping.

In a co-pending application, filed of even 10 date herewith, I have shown, described and claimed improved means for joining together the ends of a plurality of sections of sheet-metal pipe, and while said means are especially well adapted for the assembling of pipe 15 sections that are formed in the manner and by the means set forth herein, the employment of such manner and means is not limited to any specific means for end-joining.

I am aware that, due to the manifest desirability of storing and shipping sheet-metal pipe sections in the form of substantially flat blanks, and providing means whereby the side edges of each such blank may subsequently be interlocked when the 25 blank is bent to form for use, numerous efforts have been made to provide such interlocking means which would be commercially satisfactory, but, so far as I know, none of such efforts has been entirely successful, and 30 it is primarily to the overcoming of some of the objections to the side-seaming means heretofore produced, that my present invention is addressed.

The principal object of this invention is 35 to produce a substantially flat sheet-metal blank, having its two side edges provided with means for securing them together so as to form a substantially gas-tight joint, while at the same time reinforcing the pipe section 40 as regards its tendency to unitary lateral distortion, and interlocking the side edges in such a way that any appreciable slippage of said edges relative to each other is strongly opposed, if not entirely prevented under normal use of the piping.

The means by which the foregoing and other objects are accomplished by my invention, and the manner of their accomplishment, readily will be understood from the 50 following description on reference to the accompanying drawings, which depict preferred embodiments of the invention, and in which:

Fig. 1 is a broken plan view of the form of 55 sheet-metal pipe blank which I prefer to em-

ploy, as initially shaped, slotted, and scored for bending along one of its side edges.

Fig. 2 is a plan view of the blank shown in Fig. 1, after the scored side edge has been bent along the lines of scoring, and the two edges 60 of the blank have been brought together, ready to be interlocked.

Fig. 3 is a plan view of the completed pipe section after the operation of joining the side edges has been completed. 65

Fig. 4 is a sectional view, taken substantially on line IV—IV of Fig. 2.

As shown in the drawings, in which similar parts are identified by corresponding reference characters throughout the several views, 70 the blank 5, formed from an initially rectangular strip of sheet-metal by any suitable punching, cutting or other operation, has at one of its side edges 6 a series of tongues 7, which preferably are spaced uniformly, and 75 each of which comprises a long side 8, which is sharply inclined relative to the side edge 6 of the blank, a rounded end portion 9, and a short side 10, which tapers slightly away from the long side 8 toward the side edge 6, 80 and intersects said side edge at a sharply acute angle. At the opposite side 11 of the blank, it is scored along two lines 12 and 13, which are parallel with the side edge 11 of the blank, and hence with each other, and 85 along the scored line 12 a series of slots 14 are formed, one end of each of said slots lying in a line at right angles to the center line of the blank 5 and passing through the point of intersection of the long side 8 of one of the 90 tongues 7 with the side edge 6 of the blank, and the other end of the slot bearing a similar relation to the point of intersection of the short side 10 of the tongue with said side edge 6. 95

It is intended that the blanks 5 shall be stored, shipped, and if desired delivered to users, in the flat condition indicated in Fig. 1, since, due to the provision of the lines of scoring 12 and 13, the blank readily may be 100 bent manually along clearly defined, straight and parallel lines, when it is about to be formed into a pipe section. After the side edge 6 is thus bent along lines 12 and 13, into substantially the shape indicated in Fig. 105 4, the side edges 6 and 11 are brought together to form the blank into substantially cylindrical shape; the tongues 7 are inserted into their respective ones of the slots 14; and the side edges of the blank are moved manu- 110

ally parallel with each other, in a direction such as to jam an end of each of the slots 11 tightly into the sharp corner formed by the intersection of the short side 10 of the tongue 5 with the side edge 6 of the blank.

An important feature of the present invention is the provision of the lines 12 and 13 of scoring, so that the blanks may be delivered to the user in their initial flat condition, and 10 formed into pipe sections by him without the use of any special tools or equipment, which would be impossible in the absence of said scored lines. And another important 15 feature is the sharply acute angle at which the short side 10 of each tongue intersects the side edge 6 of the blank, and the absence of any rounded surface at the point of such intersection, so that one end of each slot may be wedged tightly into the corner between 20 the side 10 of the tongue and the side edge 6 of the blank, thereby forcing the opposite end of the slot against the long side 8 of the tongue at the point of intersection of said side 25 with the side edge of the blank, and bringing the side edge 6 of the blank tightly into engagement with the base of the U-shaped 30 groove formed by the bending of the blank along the scored line 12. This results in the formation of a substantially gas-tight joint 35 which does not open up when the pipe expands and contracts under temperature variations, and renders it unnecessary to bend the tongues 7 after they have been inserted into the grooves 14. In the use of any of the here- 40 tofore-devised forms of tongue-and-slot connections for joining together the side edges of sheet-metal pipe blanks, it, so far as I am aware, has been the practice, and has been necessary, to bend the tongues after they were

inserted into the slots, by turning each tongue 40 outwardly against an edge of its slot. This not only does not insure a substantially gas-tight joint when the pipe expands and contracts, but adds to the labor required in forming the pipe, and hence to its cost, and necessitates the use of a special tool or tools for bending the tongues. 45

Various modifications of minor details of the improvements disclosed herein doubtless 50 readily will suggest themselves to those skilled in this art, but such modifications fall within the scope of my inventive rights, and my invention is not to be construed as being limited to any details not specifically set out in the 55 claim.

Having now fully disclosed the invention, what I claim as new, and seek to secure by Letters Patent, is:—

A sheet-metal pipe blank having projecting from one of its side edges a series of 60 spaced tongues, and being scored near its other side edge along a line parallel with said edge, and a series of slots in the line of said score, adapted to receive said tongues, and spaced in conformity with the spacing thereof, the said tongues being sharply inclined 65 relative to the side edge from which they project, the space at the intersection of the shorter side of each tongue with the side edge being sharply angular, and for a substantial length 70 thereof of less width than the thickness of the blank whereby to provide a gripping action on the blank edge engaged thereby, the side of each tongue opposite to said shorter side closely engaging the adjacent slot edge 75 when in operative position.

In testimony whereof I affix my signature.
EDDIE O. SIMPSON.
